UNITED STATES PATENT OFFICE.

CHARLES E. POPE, OF HOLYOKE, MASSACHUSETTS.

AUTOMATIC PAPER-MACHINE.

1,183,113.

Specification of Letters Patent. Patented May 16, 1916.

Application filed April 5, 1915. Serial No. 18,098.

To all whom it may concern:

Be it known that I, CHARLES E. POPE, a citizen of the United States of America, residing in the city of Holyoke, county of 5 Hampden, and State of Massachusetts, have invented certain new and useful Improvements in Automatic Paper-Machines, of which the following is a specification.

This invention relates to a fast running 10 paper machine and particularly to improved means and arrangements of parts whereby the web is transferred automatically from the squeeze or press rolls to the driers.

The object of the invention is to provide 15 an improved arrangement of parts by which the paper making machine may automatically transfer the forward end of a fast running web from the last squeeze rolls to the first drier characterized in the provision 20 of positively acting means to force the web to follow the bottom felt from the last squeeze rolls to a point adjacent the first drier, a guiding means between the first drier and the point where the forward travel 25 of the bottom felt ends to which the running web may jump from the felt and means to automatically force the forward end of the web from the guiding means to and between the first drier and its felt.

30 Other objects will appear in the detailed description and annexed claims.

A preferred embodiment of my invention is shown in the accompanying drawings for 35 illustrative purposes and will now be described.

In the drawings: Figure 1 is a diagrammatic view of the arrangement of the parts of my invention; Fig. 2 is a side elevation 40 of a paper making machine, showing only the parts thereof pertinent to an understanding of the invention by those skilled in the art; Fig. 3 is a diagrammatic detail view of a modification of one feature of the invention; Fig. 4 is a detail plan view 45 of one feature of the invention associated with the last squeeze rolls; Fig. 5 is a detail sectional view taken on the line 5—5 of Fig. 4.

The features of the invention by which 50 on the start of the machine the web is automatically transferred from the lower felt to the driers will first be described. As well known by those skilled in the art the web, at the start or after any break in the 55 process of making the paper, must be carried through the machine and fed to the

driers either by hand or automatically. Rather than handle the entire width of the web it is customary to form on the wire a ribbon which is carried through the machine and afterward leads the web of full width for the normal operation.

Referring to Figs. 1, 2, 4, and 5, the last squeeze rolls 1 and 2 receive therebetween the lower felt 4 with the web (at first a 60 ribbon) thereon. The top roll 2 is bare so that there is a tendency for the web to stick to this roll. However, before the ribbon has followed the roll 2 any substantial distance it meets a revolving brush 3 arranged to 65 rotate oppositely to roll 2 at one side (the side along which the ribbon is customarily fed). This brush 3 preferably of wire bristles strips the ribbon from the roll and throws it down on the felt 4. The latter is 70 guided horizontally beyond the squeeze rolls to guide roll 5 adjacent the periphery of the first drier 11 where it returns over other rolls 5. In line with the upper roll 5 and between it and the first drier 11 is a guide 75 roll 30 supplied with a doctor 31. Above and a little beyond the roll 30 is a horizontally arranged pipe 32 connected to a source of air under pressure. This pipe has a 80 downwardly directed outlet as indicated in 85 Fig. 1.

Now if it is assumed that the machine is a fast running one the ribbon 6 is loosened from the roll 2 by brush 3 and the loosened end is carried by the felt 4 horizontally so 90 that it jumps the distance between adjacent rolls 5 and 30 and into line with the downwardly directed blast from pipe 32. The latter forces or blows it downwardly between the bight of drier cylinder 11 and its 95 felt 9 whereupon the ribbon is pulled down and around roll 30. If for any reason it should start to wind on roll 30 the doctor 31 will strip it off at a point above its proper entrance on drier 11. Thus the paper is automatically and efficiently transferred from the squeeze rolls to the first drier by improved means.

The manner of mounting and rotating the brush 3 is shown in Figs. 4 and 5. An 105 arm 15 pivoted to the side frame A at 17 has a horizontal bearing in which is mounted the shaft of brush 3. On the outer end of the brush is a pulley driven by any suitable driving means as 18 and 22. The brush 110 may be positioned by swinging arm 15 and claiming it as desired to frame A.

A modification is shown in Fig. 3 in which the web 6 jumps from felt 4 to the bight of suitably driven pressure rolls 19 and 21. The latter is made of rubber or an equivalent substance to press the web smoothly on bare metal roll 19. A second metal roll 20 bears on roll 19 so that the rolls 19 and 20 press the web firmly together in the absence of any felt just before the web passes to the drier. This action materially strengthens and smooths out the paper so that it will have an improved appearance or finish. A brush 8 bears against roll 20 and operates in conjunction with this roll in all respects like the brush 3 already described and of which it may be a counterpart. If the web starts to wind on roll 20 brush 8 will throw it down to enter the bight of drier 11 and its felt 9. A doctor on roll 19 is positioned to prevent the web from winding on this roll. In any case the web is directed downwardly for proper application to the first drier.

The improved arrangement of the drying cylinders will now be described. As indicated in Figs. 1 and 2 each lower cylinder 11 of a series is located with its axis vertically below its companion cylinder of the upper series. The upper and lower cylinders are arranged only a small distance apart or in such a way that the forward end of the web or ribbon as it runs rapidly through the machine may jump from the lower cylinder to the bight of the upper one and its felt without climbing an appreciable distance and thus be transferred by its momentum. To this end a doctor 40, Fig. 1, is arranged to strip the ribbon from cylinder 11 as it reaches its upper horizontal travel. The lower guide roll 41 for felt 14 directs the latter to cylinder 12 from a point just back of the doctor 40 so that as the ribbon 6 leaves drier 11 it will jump to the felt 14 traveling rapidly to drier 12 and be directed and carried to the latter drier, and this result is automatically obtained without the interposition of any structure not heretofore found in driers, but by an improved arrangement of the old structure. The web or ribbon 6 is stripped from drier 12 by a doctor as it is traveling thereon vertically and downwardly. The upper left hand guide rollers 10 and lower right hand guide rolls 41 for the lower and upper felts 9 and 14, respectively, are mounted close to their respective drying cylinders 11 and 12 as shown. The web 6, therefore, in passing from the upper driers to the lower driers travels automatically and freely exposed on both sides a vertical distance from one drier to another about equal to that between the axes of the upper and lower driers. The free space on both sides of the exposed web permits the vapor, which would otherwise be imprisoned to a large degree with the

web, to escape and thus advance the drying operation.

In addition to the automatic transferring feature of the invention from one drier to the succeeding one and the other advantages of the arrangement described it is clear that a considerable amount of floor space is saved by mounting each pair of driers substantially one above the other as described. Where the driers are arranged as heretofore in staggered or zig zag relation the distance of at least the diameter of one cylinder is necessary for a given number of driers, in excess of the space required for the improved arrangement described. This improved arrangement of drying cylinders is not claimed as a part of this invention but forms the subject-matter of my copending application, Serial No. 82,409, filed Mar. 6, 1916.

It is not thought necessary to use any space in describing the driving connections for the several parts or specific manner of mounting them in the machine. From the drawings and description disclosed one skilled in the art can readily put the invention into use.

The invention is defined in its proper scope by the appended claims rather than by the foregoing specific description.

What I claim is—

1. In a paper making machine apparatus for transferring the web in an automatic manner to the driers, comprising, a horizontally mounted felt, squeeze rolls between which the felt with the web thereon pass, means to guide the felt to a point adjacent the first drier, a guiding element mounted in line with the web on the felt and between said point and the drier, automatic means to force the free end of the web over the said element and toward the entrance of the drier, and positively operable means to strip the web from the periphery of the top squeeze roll and throw it in loosened condition on the felt, whereby the speed of the latter will cause the web to jump to said element and be forced thereover and into the entrance of the first drier.

2. In a paper making machine apparatus for transferring the web to the driers, comprising, a felt mounted to travel at high speed, squeeze rolls between which the felt with the web thereon pass, means to guide the felt beyond said squeeze rolls, and a brush operable to strip the web from the upper squeeze roll and throw it in loosened condition upon the felt beyond the squeeze rolls.

3. In a paper making machine apparatus for transferring the web to the driers including a pair of squeeze rolls, a felt, means to guide the felt between and beyond the squeeze rolls toward the drier and a rotatable brush mounted to bear against the upper squeeze roll just above the felt and

means to rotate the brush in a direction opposite to the upper squeeze roll, whereby the web which tends to stick to the upper squeeze roll is stripped therefrom and thrown in loosened condition upon the felt.

4. In a paper making machine, the combination of a set of driers, a pair of squeeze rolls, a felt arranged to carry a web between the squeeze rolls to a point adjacent the driers, means associated with the squeeze rolls to loosen the web and keep it on the felt, means spaced between the forward end of the felt and the first drier operable to directly force the web into the drier, all constructed and arranged so that the loosened web will jump the space from the felt to said means between it and the first drier.

5. In a paper making machine, a set of driers, means to guide a web carrying felt

to a point adjacent the first drier, a pair of pressure rolls spaced between the said point and drier, said rolls being in line with the web on the felt and means to direct the web from said rolls and force it toward the entrance of the first drier.

6. In a paper making machine, a set of driers, means to guide a web carrying felt to a point adjacent the first drier, a bottom pressure roll and two top rolls arranged in line with said felt to automatically receive the web therefrom, the rear top roll being of a yielding nature to press and smooth the web on the bottom roll, a brush mounted to bear against the front top roll and rotatable in the opposite direction and operable to strip the web which sticks thereto and throw it in the direction to enter the first drier.

CHARLES E. POPKE.
